PARALLEL LINE SPACING DEVICE FOR
DRAWING PURPOSES

Stefan Zaborowski, Waltham Cross, England

Application January 17, 1951, Serial No. 206,362
In Great Britain January 19, 1950

11 Claims. (Cl. 33—110)

1

This invention relates to devices for facilitating the drawing of parallel lines on technical drawings and the like and has for its object to provide an improved device of this character capable of operation by one hand whereby section lines for example, can be drawn rapidly, parallel and with accurate spacing the amount of which may be predetermined.

According to the invention a device for facilitating the drawing of parallel lines on technical drawings and the like comprises in combination; a set square having formed therein parallel to the hypotenuse side thereof an enclosed slot; a strip member of smaller length than the said slot arranged to slide longitudinally therein; at least one inclined ramp formed on said strip; resilient means secured on said set square and engaging said strip member so as normally to urge it into abutment with one end of said slot; and a depressible bridge member carrying at least one roller for engagement with said inclined ramp; said bridge member being arranged for manual depression to press said strip member into non-sliding engagement with the surface being ruled and at the same time to relieve the pressure on said set square and allow movement thereof relative to said strip member against the action of said resilient means whilst said roller moves down said ramp, the reduction of the pressure of said bridge member permitting return of said strip member to its original position under the action of said resilient means in readiness for a further operation.

According to a further feature of the invention the surface of the set square and/or the strip member which comes into contact with the drawing or the like on which it is employed is wholly or partly covered with a layer of material which gives an increased coefficient of friction between the set square and the surface of the drawing.

According to a further feature of the invention means are provided for varying within limits the interval between successive parallel lines drawn with the aid of the said device.

Reference will now be made to the accompanying drawings which illustrate two preferred forms of construction of the device according to the invention and in which:

Fig. 1 is a plan of the device according to the invention,

Fig. 2 is a section on the line II—II of Fig. 1.

Fig. 3 is a sectional elevation on the line III—III of Fig. 4 of a second form of construction of the device according to the invention, and

2

Fig. 4 is a plan of Fig. 3.

In carrying the invention into effect according to one form thereof as shown in Figs. 1 and 2, a set square 1, for example a 45° set square, has formed therein, parallel to and near the hypotenuse side 2 thereof, a rectangular slot 3. Within the said slot 3 there is arranged a strip member 4 which is shorter than the slot, one end 4a of said strip member having secured thereto one end of a resilient means such as for example, a clock spring 5, the other end of which is anchored to the upper surface of the set square at 6. Formed integral with the strip member 4 at either end thereof are two inclined ramps 4b. Arranged above and parallel to the said slot 3 is a resilient bridge member 7 consisting of a flexible strip of metal or other material bent downwardly at its end and bolted at either end to the body of the set square. The portion of the bridge member lying over the said slot has secured thereto a pair of spaced brackets 8 carrying rollers 9 the axes of which are at right angles to the longitudinal axis of the slot 3 and the strip member 4.

The stop 11 is secured in the desired position by means of a clamping screw 14 mounted in a block 15 secured to the set square 1.

The under surface of the strip member and the body of the set square or portions thereof may be wholly or partly covered with fabric or other material 13 which will provide a high coefficient of friction between the said set square 1 or the strip member 4 and the surface over which it is to be moved. Alternatively, the under surface of the set square 1 and the strip member 4 may be suitably roughened or corrugated so as to provide the necessary degree of frictional contact with the surface of the drawing.

In the use of the apparatus shown in Fig. 1 the adjustable stop member 11 is rotated about its pivot 12 so as to limit the movement of the strip member 4 in the slot 3 to an amount equal to that by which it is desired to space the parallel lines to be drawn with the apparatus, the stop being secured in its adjusted position by the clamping screw 14. The set square is then placed on the surface of the drawing, slight pressure, sufficient only to hold the set square in position being exerted on the bridge member 7, and a line drawn along one edge thereof. The resilient bridge member 7 is then pressed downwardly at or near its central point so as to bring the rollers 9 into contact with the ramps 4b such action pressing the strip member 4 into firm contact with the drawing and also relieving the pressure of the set

square 1 on the latter. Under continued downward pressure on the bridge member 7 the rollers move downwardly along the ramps 4b thus causing lateral movement of the set square 1 relatively to the strip member 4 until the end of the strip member 4 abuts the end of the slot 3, this lateral movement being determined, as stated above, by the adjustment of the stop member 11. The set square moves freely over the drawing during such movement since its pressure thereon is relieved, as stated above, by downward pressure on the bridge member 7, whilst the strip member 4 is securely retained in position on the drawing by the downward pressure exerted thereon through the rollers 9. The pressure applied to the bridge member 7 is then reduced and the rollers are thereby lifted off the inclined ramps 4b of the strip member 4 and the latter, under the action of the spring 5 returns to its original position abutting one end of the slot 3. The set square does not move during said movement of the strip member 4 since the bridge member 7 is no longer acting to relieve the pressure on the set square 1 and the covering 13 of fabric or other material on the under surface of the set square 1 ensures good frictional contact with the surface of the drawing; moreover, a slight manual pressure is still being applied to the bridge member 7, and thereby to the set square 1.

In this position another line can now be drawn along one edge of the set square and the sequence of operations just described can now be repeated for drawing a further series of parallel lines.

In the second form of construction shown in Figs. 3 and 4 the set square 21 is formed with an enclosed slot 23 in which is slidably disposed a strip member 24 the length of which is smaller than the length of the slot 23. The strip member 24 is formed intermediate its ends with an inclined ramp 24b and is urged in a direction to abut one end of said slot by means of a spring 25 one end of which is anchored in a recess 21a, on the set square 21 and the other end of which engages in a recess 24c at one end of the strip member 24. Pivotal mounted on the set square at either side of the slot 23 and intermediate the ends thereof is a bridge or trigger member 27 extending longitudinally of the slot 23 and formed with a downwardly extending bracket 28 carrying a roller 29.

As in the form of construction shown in Fig. 1 the strip member 24 may likewise be provided with means for adjusting the movement of the strip member 24 longitudinally of the slot 23. Thus the strip member 24 is provided with a recessed portion providing a straight edge 30 at an angle to the longitudinal axis of the strip member 24 whilst mounted at one side of the slot 23 and co-operating with the sloping edge in the strip member 24 is a pivotal stop 31 rotating about a pivot 32 and adapted to be secured by a clamping screw 34 mounted on a block 35.

In the operation of the form of construction of the invention shown in Figs. 3 and 4 the set square 21 is normally kept in firm contact with the drawing by light manual pressure thereon near the trigger member pivot. When it is desired to effect movement of the set square for the purpose of drawing spaced parallel lines along one edge thereof the bridge or trigger member 27 is depressed at its free end by manual or digital pressure and the pressure on the set square is counteracted by the leverage exerted

thereon through the bridge member 27, the roller 29 acting as a fulcrum. The downward pressure at the same time ensures that the strip member 24 is pressed firmly on the drawing and as the pressure is continued the roller 29 moves down the inclined ramp 24b thereby effecting movement of the set square 21 relative to the strip member 24. At the conclusion of such movement, determined by the amount of travel of the strip member 24 in the slot 23 determined by the adjustment of the stop member 11, the pressure on the bridge member 27 is released and the light manual pressure on the set square 21 (which is never completely removed during use of the device) is again applied since it is no longer counteracted by pressure on the bridge member 27. The strip member 24 then returns under the action of the spring 25 to its original position abutting one end of the slot 23, the roller travelling up the ramp 24b and the apparatus then being ready for a further operation for drawing another series of parallel lines.

It will be obvious to a person skilled in the art that many modifications may be made to the apparatus described without departing from the invention as defined in the accompanying claims. Thus, many different forms of spacing adjustment could be provided, the form of the resilient means, and its method of attachment to the strip member and set square, and the shape and construction of the bridge member may be other than those described and illustrated herein.

I claim:

35 1. A device for facilitating the drawing of spaced parallel lines comprising in combination: a set square having formed therein parallel to the hypotenuse side thereof an enclosed slot; a strip member of smaller length than the said slot arranged to slide longitudinally therein; at least one inclined ramp formed on said strip; resilient means secured on said set square and engaging said strip member so as to urge it into abutment with one end of said slot; and a deformable bridge member carrying at least one roller for engagement with said inclined ramp; said bridge member being arranged for manual depression to press said strip member into non-sliding engagement with the surface being ruled and at the same time to relieve the pressure of said set square and allow movement thereof relative to said strip member against the action of said resilient means whilst said roller moves down said ramp the reduction of the pressure on said bridge member permitting return of said strip member to its original position under the action of said resilient means in readiness for a further operation.

60 2. A device for facilitating the drawing of spaced parallel lines comprising in combination; a set square having formed therein parallel to the hypotenuse side thereof an enclosed slot; a strip member of smaller length than the said slot arranged to slide longitudinally therein; inclined ramps formed at either end of said strip member; resilient means mounted on said set square to urge said strip member into abutment with one end of said slot; a resilient bridge member mounted to extend above said slot; and a pair of rollers carried by said bridge member and arranged on depression thereof to contact said inclined ramps and press said strip member downwardly whilst relieving the pressure on said set square and effecting movement of said set square relative to said strip member as said

rollers travel down said ramps under continued pressure on said bridge member, said strip member returning to its original position under the action of said resilient means upon release of said pressure.

3. A device for facilitating the drawing of spaced parallel lines as claimed in claim 2 including the provision of a layer of material applied to a portion at least of the under surface of said set square to increase the coefficient of friction thereof.

4. A device for facilitating the drawing of spaced parallel lines as claimed in claim 2 including the provision of roughened portions on a part at least of the under surface of said set square so as to increase the coefficient of friction thereof.

5. A device for facilitating the drawing of spaced parallel lines as claimed in claim 2 including the provision of an adjustable stop member on said set square to limit the extent of movement of said strip member in said slot.

6. A device for facilitating the drawing of spaced parallel lines as claimed in claim 2 including a stop member pivoted on said set square and adapted to co-operate with an edge formed on said strip member at an angle to the longitudinal axis thereof, so as to limit the extent of movement of said strip member in said slot; and locking means for securing said stop in its adjusted position.

7. A device for facilitating the drawing of spaced parallel lines comprising in combination a set square having formed therein parallel to the hypotenuse side thereof an enclosed slot; a strip member of smaller length than said slot arranged to slide longitudinally therein; an inclined ramp formed on said strip intermediate the ends thereof; resilient means secured on said set square and engaging said strip member so as to urge it into abutment with one end of said slot; a depressible bridge member pivoted at one

end on said set square; and a roller carried on said bridge member intermediate its ends, said roller being arranged so that upon depression of the free end of said bridge member said roller contacts said ramp on said strip member and presses it downwardly and thereafter travels down said ramp whilst counteracting pressure on said set square and thereby produces movement of the latter relative to said strip member, said strip member returning to its original position under the action of said resilient means upon release of pressure of said bridge member.

8. A device for facilitating the drawing of spaced parallel lines as claimed in claim 7 including the provision of a layer of material applied to a portion at least of the under surface of said set square to increase the coefficient of friction thereof.

9. A device for facilitating the drawing of spaced parallel lines as claimed in claim 7 including the provision of roughened portions on a part at least of the under surface of said set square so as to increase the coefficient of friction thereof.

10. A device for facilitating the drawing of spaced parallel lines as claimed in claim 7 including the provision of an adjustable stop member on said set square to limit the extent of movement of said strip member in said slot.

11. A device for facilitating the drawing of spaced parallel lines as claimed in claim 7 including a stop member pivoted on said set square and adapted to co-operate with an edge formed on said strip member at an angle to the longitudinal axis thereof, so as to limit the extent of movement of said strip member in said slot; and locking means for securing said stop in its adjusted position.
